UNITED STATES PATENT OFFICE.

MICHAEL J. RENO AND ALBERT SCARAMELLA, OF NEW HAVEN, CONNECTICUT.

CRUSHING-MACHINE.

1,353,420.

Specification of Letters Patent. Patented Sept. 21, 1920.

Application filed April 15, 1920. Serial No. 374,092.

To all whom it may concern:

Be it known that we, MICHAEL J. RENO and ALBERT SCARAMELLA, citizens of the United States, residing at New Haven, in 5 the county of New Haven and State of Connecticut, have invented certain new and useful Improvements in Crushing-Machines, of which the following is a specification, reference being had therein to the accompanying drawings.

Our invention relates to new and improved crushing machines, particularly to that class of such machines as are designed for crushing or pulping fruits, vegetables 15 and the like, to separate the liquid from the solids.

It is the object of this invention, among other things, to provide a device of this character, so designed that it may be economically 20 constructed, readily and conveniently assembled and taken down and will produce the most efficient results, removing the very maximum amount of liquids from the solids operated thereon.

To these and other ends our invention consists in the crushing machine having certain details of construction and combinations of parts as will be hereinafter described and more particularly pointed out in 25 the claims.

In the drawings accompanying this specification and made part hereof and in which like numerals of reference designate like parts in each of the figures,

Figure 1 is a fragmentary side view of our improved device assembled, and

Fig. 2 is an end view thereof partly in section, the sectional parts being taken substantially upon line 2—2 of Fig. 1.

In the practice of our invention, we provide a body member 10 having a chamber 11 therein which opens into a funnel 12 upon one side thereof, as is usual in meat choppers and the like.

Rotatably mounted in the body 10 is a stub shaft 13, a portion 14 thereof being rectangular in cross section, shown herein as square, with a collar 15 thereon. Surrounding this shaft with its head normally in contact with one end of the chamber 11 is a cup 16 between which and the collar 15 is a coil spring 17. The crank 18 having a separable engagement with the stub shaft 13 provides means for rotating said shaft. A gear or other similar device may be sub-

stituted for the crank 18 if desired, as a source of power for rotation of said stub shaft.

Detachably connected to one side of the body member 10 is a sieve frame 19 having a substantially circular head 20 at one end, and a flaring mouth discharge collar 23 at the other end connected with the head by the tie bars 24, shown herein as two in number. The number of tie bars may however be varied. Ears 21 which project radially from the head 20 engage the dogs 22 on the body member and provide means for detachably securing the sieve frame to the body member, a gasket 25 forming a liquid tight joint. Within the sieve frame is a conical sieve 26 which abuts at its outer end against the shoulder 27, upon the inside of the said frame.

Rotatably mounted within the chamber 11 and the sieve 26 is the screw or worm 28 upon the outside of which is the groove 29, that extends from one end of the screw to the other and the depth of which decreases as it approaches the smaller end of the screw. One improved device is attached to a table, shelf or other desired place by means of the clamp 30, having a foot 31 integral therewith and opposite which is the screw 32 threaded through the clamp.

In operation the fruit, vegetables or the like are placed into the funnel 12 from which they pass into the chamber 11 and as they come in contact with the rotating screw or worm 28 are picked up by the groove 29 and carried toward the outer end thereof at the same time being crushed and the liquid therein escaping through the sieve 26 into a receptacle (not shown) conveniently arranged to receive it. The solids, that is the pulp, seeds and skins do not pass through the sieve, which is of such fine mesh as to prevent the same, but continue to travel in the groove 29 until they come to the end of the groove adjacent to the shoulder 27. When sufficient solids have accumulated thereat the continuous pressure of the oncoming solids forces the same against said shoulder and the screw 28 is moved axially by reason thereof, away from said shoulder against the action of the spring 17, at which time the solids escape from the screw and sieve and through the discharge collar 23 into a receptacle, also conveniently arranged to receive it, this latter not being shown.

As soon as the resistance of the spring overcomes the pressure of the solids the spring 17 returns the screw axially to its original position with its smaller end 5 against the collar 27 and it there remains until moved endwise again by the pressure of the solids, within the sieve 26.

An operative engagement between the screw 28 and the stub shaft 13 is created, 10 by the angular portion 14 of said stub shaft which enters an opening in said screw, having substantially the same cross section as said shaft, at this point. Means are thus provided for easy and ready assembly and 15 still provide an efficient and operative engagement between the stub shaft and screw. No liquid can escape through the discharge collar 23 because of the engagement of the end of the screw 28 with the shoulder 27, 20 and when the screw 28 is moved endwise away from said shoulder, the solids escaping from the screw prevent leakage of liquid therethrough, and in addition to this the tendency of the liquid would be to flow 25 toward the body member 10, and away from said collar, this being the largest diameter of the sieve 26.

Minor changes and alteration may be made within our invention aside from those 30 herein suggested and we would therefore have it understood that we do not limit ourselves to the exact construction herein shown and described but claim all that falls fairly

within the spirit and scope of the appended claims.

35

Having described our invention, what we claim as new and desire to secure by Letters Patent, is:

1. In a crushing device, a body, a rotary and longitudinally movable screw therein, 40 said body having opposite dogs extending outwardly therefrom, a sieve frame including a head rotatably engaged with the body and having ears engageable with the dogs, a mouth, spaced longitudinal tie bars having 45 flat uninterrupted inner faces connected at their ends to the mouth and head, and a sieve in the frame arranged between the bars and between the head and mouth and engaged with said flat uninterrupted faces of the 50 bars.

2. In a crushing device, a body, a rotary and longitudinally movable screw therein, a sieve frame including a head, a mouth, spaced longitudinal tie bars having flat uninterrupted inner faces connecting the head and mouth, and a sieve in the frame arranged between the bars and between the head and mouth, and engaged with said flat uninterrupted faces of the tie bars, said tie 60 bars acting to assume stresses imposed by the pulp on the mouth.

55

In testimony whereof, we have hereunto affixed our signatures.

MICHAEL J. RENO.
ALBERT SCARAMELLA.
